UNITED STATES PATENT OFFICE.

JOSEPH NEFCZESAU SKAS, OF CLEVELAND, OHIO.

DOOR CHECK.

1,402,641.

Specification of Letters Patent. Patented Jan. 3, 1922.

Application filed September 7, 1921. Serial No. 493,979.

To all whom it may concern:

Be it known that I, JOSEPH NEFCZESAU SKAS, a citizen of the United States, residing at Cleveland, in the county of Cuyahoga and 5 State of Ohio, have invented certain new and useful Improvements in Door Checks, of which the following is a specification.

This invention relates to door checks and particularly to that class of such devices 10 adapted to be attached to a swinging door to insure of the same to close automatically from normal open positions of use.

An object of the invention resides in the construction of a door check of the pneumatic and piston operated type designed to be attached to any style or type of swinging door or closure, and including provision for regulating the door check when used in connection with heavy or light doors to produce 20 a gradual or quick closing operation of the same.

A further object of the invention resides in the construction of a pneumatic, adjustable door check wherein the operative parts 25 are completely concealed to prevent the admission of dust or dirt which might effect the same from proper functioning and in addition to deter unauthorized persons from disarranging or damaging any of its parts. 30 Another important object of this invention will be found to reside in a novel and improved door check of the type set forth which includes provision whereby the door check may also be utilized to hold a door in 35 desired open position when certain of the parts of the check are thrown past a dead center by the opening movement of the door beyond that predetermined by the adjustment of the check for its automatic closing 40 operation.

An additional object of the invention is directed to a pneumatic door check capable of universal use with practically any type of swinging closure and one which is extremely 45 simple in construction, consisting of comparatively few parts therefore inexpensive to manufacture, highly efficient and positive in operation, strong, durable and easily adjustable so as to meet the various requirements 50 to which the invention may be put and otherwise capable of being installed without considerable labor or mechanical skill.

With these objects in view and others 55 which will be suggested and manifest as the purpose and nature of my invention are revealed in the following specification and

drawing wherein I have shown but one preferred embodiment thereof,

Figure 1 is a front elevation of the door 60 check ready to be applied to a door.

Fig. 2 is a longitudinal vertical section thereof.

Fig. 3 is a longitudinal section taken on the line 3—3 of Fig. 2.

Fig. 4 is a perspective view showing the 65 door check in position on a door or closure.

Referring now to the drawings wherein like numerals designate corresponding parts throughout the specification, 5 designates a cylinder or casing which as shown is provided with an externally, threaded end 6, for threaded engagement with a collar 7 internally threaded as at 8 as clearly shown in Figs. 2 and 3 of the drawing. The cylinder 5 is open at one end and closed at its outer 75 end 9, a screw threaded element 10 being provided in said closed end and has a right angular extending aperture 11 communicating with the interior of the casing for a purpose presently to appear. 80

As shown, the collar 7 is preferably formed integral with a bottom plate 12 formed with a boss 13 for receiving a bushing 14 therein, the said bottom plate being provided with a right angular extending flange 15 provided 85 with open slots 16 whereby the door check may be secured in rigid position to a door D in a manner suggested by Fig. 4 of the drawing. A top plate 17 is also provided with a boss 18 receiving a bushing 19 and is held in 90 spaced relation from the bottom plate 12 by means of a plurality of sleeves 20, and is secured to the bottom plate 12 by fastening elements 21 passing through said sleeves, whereby the vertical, squared operating shaft 21' 95 is positioned for rotation with the bushings 14 and 19 in the bosses 13 and 18 during movements of operating lever 22 and its pivotally connected lever 23 secured to the wall by a bracket 24 as shown, which levers 22 and 23 are operable with equal facility from either of the opposite sides of the cylindrical casing as may be desired or necessary in the proper mounting of the check on a door. This lever 23 is longitudinally adjustable to 100 adapt the device for use on doors of various sizes, and correspondingly to permit of the proper cooperation of the check device with a particular sized door for the desired purposes. The top plate 17 is also provided with an angularly extending flange 25 having 110 open slots 26 therein for attachment to the

door or closure to which the invention is to be applied.

Keyed to the square shaft 21' and in spaced relation thereon, I have provided a pair of 5 cam shaped plates 27, 28 which are provided with a plurality of apertures 29, said apertures being disposed in alignment for receiving a pin 30 which passes through an aperture in the bent end 31 of a piston rod 32, 10 the opposite terminal of said rod 32 being pivotally secured as at 33 in the bifurcated extension 34 of a piston 35 which is freely operable in the cylinder above referred to.

A spring 36, preferably in the form of a 15 coil of flat spring metal, is positioned within said cylinder and on the rod 32, and has one end bearing against the piston 35 and its opposite end bearing against an annular flange 7' inwardly of the collar 7. As shown, 20 the lever 22 is preferably formed integral with the vertical shaft 21', and since the door check is secured in its rigid position and moves with the door, the shaft 21' will be rotated on its axis and consequently move the 25 cam shaped plates 27 and 28 and the rod 32 inwardly against the resistance of the spring 36 and upon release of the door, the spring will return the parts to their normal position. The right angular aperture 11 formed in the 30 screw threaded element 10 permits the air to escape from the interior of the cylinder during the closing operation, and since this opening is very small, it will be readily apparent that the closing of the door will take 35 place quite gradually. By moving the screw 10 inwardly or outwardly of the end wall 9, the area of the aperture 11 may be decreased or increased correspondingly, whereby to vary the air compression within the cylinder 40 for controlling the rate of movement of the piston therein.

By reason of the adjustment permitted between the lever 32 and the cam shaped plates 27 and 28, it will be obvious that the door 45 check may be regulated to effect a quick or a slow closing operation of the door and furthermore when the spring door check is used in connection with heavy or light doors, the adjustments may be made in advance depending on the desired effect which is required.

A further feature of the invention, it will be noted, is that, when the plates 27-28 and the curved end 31 of the connected lever 55 32 are thrown over past the dead center of the vertical shaft 21', as shown in dotted lines in Fig. 3, the door, to which the door check is secured, will be maintained in its open position as long as desired, but when 60 the parts are moved in a reverse direction, correspondingly with the initial movement of the door to closed position, the spring 36 will act to effect the closing operation of the device, and will move the door to full closed 65 position. The door may be held in any de-

sired or predetermined open position correspondingly with the adjustments made between the cam shaped plates 27-28 and the curved end 31 of the lever 32, as above indicated and described. The metallic strip 70 designated by 36' is secured by screw fastening elements 37 in the respective top and bottom plates and of course prevents the admission or entry of dirt or dust into the operative part of the door check and in addition prevents unauthorized persons from disarranging or tampering with the structure. 75

In the accompanying drawings, I have illustrated my invention embodied in one 80 form by way of example, and which in practice has been found to be highly satisfactory in obtaining the desired results. It will be obvious however that other embodiments may be adopted and that various changes 85 in the details of construction may be resorted to by those skilled in the art without departing from the spirit and scope of the invention. It is furthermore understood that the invention is not necessarily limited 90 or restricted to the precise elements shown except in so far as such limitations are specified in the subject matter being claimed.

What I claim is:-

1. In a door check the combination of a 95 cylinder having a discharge opening therein a casing detachably connected to said cylinder, a laterally extending arm and operating shaft rotatably carried by said casing, a pair of cam shaped plates keyed on said operating shaft, a bent lever connected to said plate and extending within said cylinder, means for adjusting said lever with respect to said plates, and a spring controlled piston connected to the opposite end of said lever 100 for actuating said arm and its shaft as the door returns to its closed position.

2. In a door check the combination of a cylinder having a discharge opening therein, spaced plates detachably connected to 105 said cylinder, a laterally extending arm and an operating shaft rotatably carried by said plates, cam shaped elements keyed on said operating shaft between said plates, an adjustably mounted lever connected at one end 110 to said elements and extending within said cylinder, a piston pivotally connected to the opposite end of said lever and a resilient spring for actuating said arm and its shaft as the door returns to its closed position. 115

3. In a door check the combination of a cylinder having a discharge opening therein, a casing detachably connected to said cylinder and at right angles thereto, a laterally extending arm and operating shaft rotatably carried by said casing, complementary 120 cam shaped plates keyed on said shaft, a bent lever adjustably connected to said plates and extending within the cylinder, a spring controlled piston pivotally connected 125 to the opposite end of said lever and a resilient spring for actuating said arm and its shaft as the door returns to its closed position. 130

to the opposite end of said lever whereby the arm and its shaft is actuated to return the same to normal position as the door is closed, and means whereby the door is maintained in its open position when the plates are thrown past their dead center.

4. In a door check, the combination of a cylinder having an opened end and a closed end, said closed end being provided with a discharge opening therein, a pair of connected plates and a collar secured thereto for detachable connection with said cylinder, aligned bosses formed on said plates, a laterally extending arm having an operating shaft and bushing therefor rotatably carried by said plates, cam shaped elements keyed in spaced rela-

tion on said shaft and between the plates, an adjustably mounted bent lever having one end pivotally connected to said cam shaped elements and extending within the cylinder, a piston having a bifurcated extension within said cylinder and pivotally connected to the opposite end of said lever, a resilient spring within the cylinder for actuating said lever and shaft as the door returns to its closed position and a closure strip secured to the plates for preventing the admission of dust or dirt between the same and to the interior of said cylinder.

In testimony whereof I affix my signature hereto.

JOSEPH NEFCZESAUSKAS.
